DESIGN FOR A WRENCH

Donald L. Sperry, Overland Park, Kans.

Application September 23, 1943, Serial No. 111,192

Term of patent 3½ years

(Cl. D54—16)

To all whom it may concern:

Be it known that I, Donald L. Sperry, a citizen of the United States, residing at Overland Park, in the county of Johnson and State of Kansas, have invented a new, original, and ornamental Design for a Wrench, of which the following is a specification, reference being had to the accompanying drawing, forming a part thereof.

Fig. 1 is a side elevational view of the wrench, showing my new design.

Fig. 2 is an edge elevational view thereof; and
Fig. 3 is an end elevational view thereof.

I claim:

The ornamental design for a wrench, as shown.

DONALD L. SPERRY.
